APPARATUS FOR SEALING CONTAINERS

Harry E. Stover, Connellsburg, Pa., assignor to
 Anchor Hocking Glass Corporation, Connells-
 ville, Pa., a corporation of Delaware

Application February 16, 1943, Serial No. 476,065

11 Claims. (Cl. 226—80)

My invention relates to apparatus for sealing containers. It has to do, more particularly, with an apparatus for applying closures to containers such as food containers and including jars, bottles, cans, et cetera, and sealing them on the containers.

This application is a continuation-in-part of my co-pending application Serial No. 418,401, filed November 8, 1941, which has matured into Patent No. 2,346,118, patented April 4, 1944.

In said application Serial No. 418,401, I disclose a sealing machine including a sealing unit which is actuated whenever a container, with a cap loosely positioned thereon, is moved into association with the sealing unit in sealing position. The actuating means for the sealing unit includes fluid-actuated mechanism which is controlled by means of a main control valve that is actuated each time a container with a cap thereon is moved into sealing position.

One of the objects of my present invention is to provide controlling means for a sealing unit of the type indicated which is more positive and efficient in operation.

Another object of my invention is to provide controlling means for a sealing unit of the type indicated which is of simple structure.

Another object of my invention is to provide controlling means for a sealing unit of the type indicated which requires very little adjustment and which is easy to maintain in proper working order.

Another object of my invention is to provide controlling means for a sealing unit of the type indicated which is of such a nature that it cannot be jammed by a container and, therefore, there is no danger of the parts thereof being bent or broken.

Another object of my invention is to provide a magnetic means for lifting the cap from the container after it has been loosely applied at the cap-feeding position and before it reaches the sealing head.

My invention is embodied in a simple apparatus for applying closures to and sealing them on various containers such as jars, bottles, cans, et cetera. The general structure of the apparatus is substantially the same as that disclosed in my co-pending application Serial No. 418,401. This apparatus is in the form of a very compact structure which may be associated with any suitable type of conveyer unit, which is adapted to bring the containers into association therewith. The apparatus is preferably disposed in superimposed relationship to a continuously moving

conveyer upon which the filled containers are placed indiscriminately. This conveyer preferably has means associated therewith for centering and maintaining the containers centered on this conveyer. My invention also embodies a means for lifting the cap from the container as the container is moved from the cap-applying unit to the cap-sealing unit.

The apparatus may include a cap-feeding and applying unit, where caps or other closures are loosely positioned on the upper ends of the containers moved into association therewith by the conveyer. Directly adjacent the cap-feeding and applying unit, a sealing head is provided. The conveyer moves the containers, with caps loosely applied thereto, into association with this sealing head. The sealing head is spaced slightly above the upper ends of the containers and fluid-actuated means is associated therewith for forcing it downwardly whenever a container, having a cap properly associated therewith, moves beneath the sealing head. A very simple, positive and effective control arrangement is provided for starting operation of the sealing head at the proper instant.

The control arrangement includes a main control valve for controlling the supply of fluid to the fluid-actuated means which moves the sealing head. The control valve is actuated by means of a trigger. This trigger is engaged by a cap on a container when the container is moved into sealing position beneath the sealing head. The trigger is yieldingly mounted for upward movement to eliminate any danger of bending or breaking of the trigger.

The preferred embodiment of my invention is illustrated in the accompanying drawings, wherein similar characters of reference designate corresponding parts and wherein:

40 Figure 1 is a side elevational view of a machine constructed in accordance with my invention.

Figure 2 is a plan view of the machine shown in Figure 1.

Figure 3 is a longitudinal vertical sectional view 45 of the machine illustrating the sealing head unit and its operating mechanism and showing the control valve in normal position.

Figure 3a is a transverse sectional view taken substantially along line 3a—3a of Figure 3.

50 Figure 4 is a view, partly in side elevation and partly in vertical section, of the machine, showing the control valve in operative position, and

Figure 4a is a detail in perspective of the pivot structure provided for the operating trigger.

55 With reference to the drawings, I have illus-

trated a machine of the general type disclosed in my co-pending application Serial No. 418,401. It comprises generally a conveyer unit 1, a cap-feeding and applying unit 2 and a sealing head unit 3. The conveyer unit preferably embodies means for continuously moving the containers into proper association with the units 2 and 3, including means for centering the containers relative to said units.

My invention is not limited to use with any particular type of container and cooperating cap but for illustrative purposes I have shown in Figure 3 a container 4 adapted to receive the cap 5 on its upper end. This cap preferably embodies a substantially disk-like portion 6 which has a depending annular skirt 7 which carries an annular gasket 8 therewithin. When the cap is forced downwardly onto the upper end of the container, the frictional contact of the gasket with the upper end of the container will aid in maintaining the cap in position and will seal the cap on the container.

As described in said co-pending application, the containers 4 are placed at random on the conveyer and are moved in the direction of the arrows (Figures 1 to 4) by the conveyer. The containers are centered thereon and are first carried to the cap-feeding and applying unit 2. This unit is of such a type that it will apply a cap loosely to the upper end of the container. After the container passes the unit 2, it passes to the sealing head unit 3. This sealing head unit 3 is substantially the same in its main structure as that disclosed in my co-pending application.

The units 2 and 3 are disposed directly adjacent each other. They are both supported by a horizontally disposed casting 9. The casting 9 is supported at a point spaced above the conveyer unit 1 by means of a plurality of vertically disposed posts 10. As described in my co-pending application, the casting 9 may be adjusted vertically on the posts 10 to vary the height of the units 2 and 3 above the conveyer 1 for different heights of containers.

As described in my co-pending application, the sealing head unit 3 comprises a vertically disposed cylindrical housing portion 23, which has a base portion 24 that is bolted to the upper surface of the casting 9. Beneath the base portion 24 (Figure 3), the casting 9 is provided with a large opening 25, in order to permit vertical movement of the sealing head 26. This sealing head embodies a substantially cylindrical portion of non-magnetic metal which is carried on the lower end of a plunger 27 which fits tightly within housing 23 for vertical reciprocation therein. In order to normally maintain the plunger 27 in its uppermost position a spring 37 is provided.

Within the upper portion of housing 23 a plunger 40 is mounted for slidable vertical movement. A spring 42 is associated with plunger 40 and normally forces it downwardly. As described in my co-pending application, the position of the plunger relative to housing 23 may be adjusted by means of rotation of collar 46 on the threaded upper portion thereof. Also, the downward force exerted by spring 42 may be varied by rotating sleeve 39 in collar 38.

It will be apparent that the plungers 40 and 27 are disposed in axial alignment. It will also be apparent that the lower end of the plunger 40 is spaced above the upper end of plunger 27. The lower end of plunger 40 carries a roller 50 which projects beyond the extreme lower end

thereof. The upper end of the plunger 27 carries a roller 52 which projects beyond the extreme upper end thereof. Between the rollers 50 and 52 a wedge member 49 is disposed. This wedge member 49 extends through oppositely disposed vertical slots 51 and 51a formed in the wall of housing 23. The wedge member 49 is adapted to be reciprocated and is of the particular shape shown.

10 The wedge member 49 is formed on the outer end of a piston rod 56. The wedge member 49 is normally in the position indicated in Figure 3. Below the outer end of the wedge member I provide a bumper or cushioning member 57 as described in my copending application.

15 The actuating mechanism for the sealing head 26 is normally in the position illustrated in Figure 3. The plunger 40 will be held in its lowermost position by the spring 42. The plunger 27 will be held in its uppermost position by the spring 37. The wedge member 49 will be in the position illustrated in this figure. It will be apparent that if the piston rod 56 is moved to the right (Figure 3), the wedge member 49 will exert a wedging action between the rollers 50 and 52. The spring 42 will be of such strength that normally it will not be compressed by this wedging action. Consequently the plunger 27 will be forced downwardly against the action of the spring 37 and, therefore, will force the sealing head 26 downwardly. Movement of wedge member 49 to the right will cause its outer end 53 to swing downwardly as the sealing head and plunger 27 are forced downwardly. When the member 49 reaches the end of its stroke in this direction, the outer end 53 of member 49 will contact with and will be cushioned by the bumper 57.

20 As soon as the piston rod 56 moves to the left, the spring 37 will return member 26 to its uppermost position. The spring-pressed plunger 40 is provided to limit the downward force exerted on the plunger 27 to a predetermined maximum, so as to prevent injury to the container being sealed. This predetermined maximum may be varied as previously indicated. Adjusting the plunger unit 40 vertically by means of the member 46, as previously described, will vary the extent of the downward movement of the plunger 27 and, consequently, of the member 26.

25 For controlling movement of the piston rod 56, I provide a fluid-operated cylinder and piston unit 59. This unit 59 includes a housing 59a which has a large cylinder bore 60 formed in its upper portion and a small cylinder bore 61 formed in its lower portion. The bores 60 and 61 are horizontally disposed and are parallel with each other. The housing 59a is mounted on the upper surface of the casting 9 directly adjacent the housing 23. It is provided with a flattened lower surface which rests on the upper surface of casting 9. The general structure of unit 59 is similar to that described in my co-pending application.

30 The bore 60 has a hollow piston 69 slidably mounted therein. The inner end of the piston rod 56 (Figure 3) is pivotally connected to piston 69 in the manner described in Serial No. 418,401. Also, as described in said application a cushioning or buffer structure, indicated generally by numeral 56g is provided for stopping movement of the piston 69 to the right. A cap 72 is bolted to the other end of the housing 59a and is provided with an opening 74. The piston

rod 56 passes inwardly through this opening into the interior of the bore 60. The opening 74 is larger than the piston rod 56 so as to permit limited movement of the piston rod therein. A compression spring 77 is disposed within the bore 60 in surrounding relationship to the rod 56 and normally tends to force the piston 69 to the left as indicated in Figure 3. When piston 69 is moved to the right (Figure 4) it will move the wedge 49 to the right.

I preferably employ steam as the fluid for moving the piston 69 from the position indicated in Figure 4. The housing 59a has a steam jacket 80 formed in the wall thereof and extending completely around the housing. This jacket is suitably connected to a steam line 81. This jacket serves to prevent or decrease condensation of the steam within the housing 59a. The jacket also serves as a source of supply for operating the sealing mechanism, as will later appear.

The bore 61 has a piston type valve 82 mounted for axial movement therein, as shown best in Figures 3 and 4. This piston valve 82 is adapted to control the supply of steam to and exhaust of steam from the cylinder bore 60. It is mounted for axial movement within a sleeve 61a which is mounted in bore 61. The piston valve 82 is provided with axially spaced annular chambers 83 and 84. At one of its ends the piston valve 82 is provided with a projecting portion 85.

The top surface of the sleeve 61a is provided with a longitudinally extending groove or recess 86. Intermediate the ends of this recess at longitudinally spaced points slots 83a and 84a are formed which communicate with the interior of the sleeve. The left-hand end of groove 86 is closed but the right-hand end communicates with a substantially semi-circular groove 87 extending around the outer surface of the sleeve. This groove 87 is provided with a pair of slots 88 at the sides of the sleeve which communicate with the interior thereof. Also formed at each side of sleeve 61a is a flattened portion which provides a chamber 89 that connects two longitudinally spaced segmental slots 90. The slots 90 extend through the wall of the sleeve. The groove 86 in the top of the sleeve communicates with a longitudinal passage 91 formed in the wall of bore 60. This passage 91 communicates at one end with an opening 92 which leads into the left-hand end of bore 60. Each of the chambers 89 at the sides of the sleeve 61a is connected by an opening 93 to the steam chamber 80.

In order to normally maintain valve piston 82 in the position indicated in Figure 3, I provide a compression spring 94 (Figures 3 and 4). This spring 94 is disposed in surrounding relationship to a pin 95 which is threaded into the end of valve piston 82. This pin 95 extends outwardly through a cap 96, on the end of bore 61, into a tubular housing 97. The cap 96 and housing 97 are bolted to housing 59a by bolts 98. The inner end of spring 94 bears against cap 96 and fits in a socket 96a formed therein. The outer end of spring 94 surrounds a tubular portion formed on an adjusting nut 99. The nut 99 is threaded on the outer end of pin 95. It will be apparent that spring 94 will keep member 82 to the left. The resistance exerted by this spring to movement to the right may be varied by adjusting nut 99 on pin 95.

The piston valve 82 is adapted to be moved mechanically to the right. For accomplishing this movement, I provide a pivoted lever 115

which is pivoted for movement in a vertical plane. The extension 85 on the right-hand end of member 82 is pivotally connected to a link 100. This link 100 extends through a vertical slot 101 formed in a cap 102 bolted to housing 59a. The outer end of link 100 is pivotally connected to the upper end of an inclined portion 103 of lever 115. The lower portion of the lever 115 is straight and a finger 132 is formed at the extreme lower end thereof. The lower portion of lever 115 is disposed in a vertical slot 131 formed in the sealing head 26. The lever 115 is pivoted, at the point where its straight lower portion connects to the inclined upper portion 103, as indicated generally by numeral 117. This permits vertical swinging movement of lever 115.

The pivot structure 117 is illustrated best in Figure 4a. As shown, the lever 115 is disposed in a slot 104 formed in a block 105. The block 105 is bolted to a horizontal extension 106 projecting from the lower edge of cap 102. At each side of slot 104 the block 105 is provided with a cradle 107 which are in alignment with each other. The cradles 107 receive the oppositely extending portions 108 of a pivot pin carried by the lever 115. For holding the portions 108 of the pivot pin in cradles 107, I provide a leaf-spring 109 which has its inner end fastened by screws 110 to the upper surface of member 105. The outer end of the horizontally disposed leaf spring 109 is provided with a slot 111, aligning with slot 104, and on each side of this slot the spring carries a rivet 112. The rivets 112 are disposed above portions 108 of the pivot pin and keep these portions in the cradles 107. However, upward yielding movement of the pivot pin portions 108 in cradles 107, against the force of spring 109, will be permitted when necessary. Thus, lever 115 is pivotally carried by an upwardly yieldable pivot structure.

With the piston 82 in the position indicated in Figure 3, steam will exhaust from the left-hand end of the cylinder bore 60, through opening 92, passage 91, groove 86, groove 87, exhaust slots 88 and finally out through slot 101. The piston 82, when in the position indicated in Figure 3, will cover the inlet openings 90. Consequently, steam will not be supplied to the cylinder bore 60.

When piston 82 is moved to the right, as shown in Figure 4, by movement of lever 115 by means of a cap engaging the lower end thereof in a manner to be described, the steam inlets 90 are exposed allowing steam to enter annular chambers 83 and 84 and the exhaust slots 88 are covered by the piston. Steam from chambers 83 and 84 will flow through openings 83a and 84a, into groove 86, passage 91, and through opening 92 into the left-hand end of bore 60. This will move piston 69 to the right and actuate the sealing unit. As soon as lever 115 is released, the spring 94 will return valve piston 82 to the original position shown in Figure 4. This will permit exhaust of steam from the left-hand end of bore 60 and permit spring 77 to return the piston 69 to its original position.

When the conveyor moves a container beneath the cap-feeding unit 2, a cap will be applied loosely to the upper end of the container. The cap and container will be moved along until they pass beneath the sealing head 26. As described in my co-pending application, it is desirable to provide means to lift the cap from the container before it reaches the sealing head 26 to be sure that the cap does not stick on the container. I provide a longitudinally extending plate 165

which is supported beneath plate 9 and extends from the cap-feeding unit 2 to the sealing head 26 (Figure 2). This plate 165 (Figures 3 and 3a) has a plurality of magnets 166 of cylindrical form disposed in horizontal sockets 165a extending from one side edge of the plate 165 to the other and being open at both ends. A strip 165b is secured to each edge of plate 165 for the purpose of retaining the magnets 166 in their sockets. The strips 165b have their lower edges flush with the lower surface of plate 165. The sealing head 26 also has means associated therewith for lifting the cap slightly from the container. This means comprises a plurality of small magnets 174 (Figure 3) which are arranged in circumferentially spaced relationship. The head 26 and plate 165 are of non-magnetic material. The strips 165b are of magnetic material. These strips 165b will be magnetized, by magnetic flux flowing from the ends of magnets 166 into the strips, and will serve to lift the caps. This magnet structure will lift each cap from the container as the container is moved therebeneath toward the sealing head 26.

As the container with the cap thereon moves beneath the sealing head 26, the forward edge of the cap will first be lifted by a magnet 174. Continued movement of the container will cause the magnets to act on the cap to hold it up against the lower surface of the member 26. Even with the cap in firm contact with the member 26, the skirt of the cap will still surround the upper end of the container so that it will be moved along with the container. However, the cap will be spaced sufficiently from the upper end of the container to permit steam to be injected therein in the manner described in my co-pending case. When the cap moves into contact with the finger 132 of lever 115, the operation of the sealing head will be initiated.

The cap, when it engages finger 132, swings lever 115 about pivot 117. This draws the valve 82 to the right, as previously described, and operates the cylinder and piston unit 59, which, in turn, moves sealing head 26 downwardly. As the sealing head moves downwardly, it forces the cap 5 downwardly on the container into sealed position. This will move the cap out of contact with the finger 132 of the lever 115, permitting the spring 94 to return the valve piston 82 and lever 115 to their initial positions shown in Figure 3. Because of the straight lower portion of the trigger lever 115, the finger 132 will tend to swing up out of the path of the cap as it is moved by the cap about its pivot. Thus, after the sealing unit is actuated by engagement of the cap with the container, the trigger will be quickly moved out of contact with the cap by upward swinging of the lower end of the trigger and downward movement of the cap caused by downward movement of sealing head 26. The pivot point 117 of the trigger lever 115 will yield upwardly when necessary to prevent jamming and, consequently, bending or breaking of the trigger. The arc in which the trigger finger 132 moves is such that at its highest point, cap 5 may really pass therebeneath without either bending it or jamming. This is another safety measure in case the sealing head 26 does not descend to move cap 5 out of contact with the finger 132.

It will be apparent from the above description that I have provided controlling means for a sealing unit of the type indicated having many advantages. The controlling means is positive and efficient in operation. It is of simple struc-

ture. It requires very little adjustment and is easy to maintain in proper working order. Furthermore, it is of such a nature that it cannot be jammed by a container.

Various other advantages will be apparent from the preceding description, the drawings and the following claims.

Having thus described my invention, what I claim is:

- 10 1. Apparatus of the type described comprising a support for a container which has a cap positioned loosely on the upper end thereof, a sealing head disposed above the support, means for moving said container and the sealing head relative to each other to seal the cap on the container, a control unit for controlling said moving means, said control unit including means for lifting the cap from the container substantially into contact with said sealing head, a trigger for initiating movement of said moving means which is so disposed that it will be engaged by the cap while the cap is so lifted, and upwardly yieldable means for supporting said trigger.
- 15 2. Apparatus according to claim 1 wherein a pivot structure is provided for supporting said trigger for movement in a vertical plane, said pivot structure including a pivot pin, a cradle for the pivot pin, and upwardly yieldable resilient means for holding said pivot pin in said cradle.
- 20 3. Apparatus according to claim 1 wherein a pivot structure is provided for supporting said trigger for movement in a vertical plane, said pivot structure including a pivot pin, a horizontally disposed support having a slot in which the trigger is disposed, pivot cradles in said support at opposite sides of the slot for receiving said pivot pin, a leaf spring superimposed on said support and having a slot in alignment with said first-named slot, and means carried by said spring for engaging the pivot pin to yieldingly hold it in the cradles.
- 25 4. Apparatus of the type described comprising a conveyer for supporting a container, means for loosely applying a cap to the upper end of the container a sealing head disposed above the conveyer, fluid-actuated means for moving the container and the sealing head relative to each other to seal the cap on the container, a control unit for controlling said moving means, said control unit including a single control valve, magnetic means for lifting the cap from the container substantially into contact with said sealing head, a trigger for actuating said valve which is so disposed that it will be engaged by the cap while the cap is so lifted, and upwardly yieldable means for supporting said trigger.
- 30 5. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 35 6. Apparatus according to claim 4 wherein a pivot structure is provided for supporting said trigger for movement in a vertical plane, said pivot structure including a pivot pin, a horizontally disposed support having a slot in which the trigger is disposed, pivot cradles in said support at opposite sides of the slot for receiving said pivot pin, a leaf spring superimposed on said support and having a slot in alignment with said first-named slot, and means carried by said spring for engaging the pivot pin to yieldingly hold it in the cradles.
- 40 7. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 45 8. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 50 9. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 55 10. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 60 11. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 65 12. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 70 13. Apparatus according to claim 4 wherein a pivot structure is provided for supporting said trigger for movement in a vertical plane, said pivot structure including a pivot pin, cradle for the pivot pin, and upwardly yieldable resilient means for holding said pivot pin in said cradle.
- 75 14. Apparatus according to claim 4 wherein a

spring is provided for resisting movement of said valve into actuating position, said spring being adjustable.

8. Apparatus according to claim 4 wherein said valve includes a reciprocable piston, said mechanical connection being at one end of said piston, an extension on the other end of said piston, said extension having a compression spring associated therewith for resisting movement of said valve into actuating position, and means for adjusting the force exerted by said spring.

9. Apparatus for sealing containers comprising a conveyer, a cap-applying unit and a cap-sealing unit disposed at longitudinally spaced positions of the conveyer, means disposed between said units for lifting caps from the con-

tainers as they are moved from the cap-applying unit to the sealing unit, said means comprising a longitudinally extending magnetic bar disposed above the path of travel of the caps carried by the containers and closely adjacent thereto.

10. Apparatus according to claim 9 wherein the bar is in the form of a pair of longitudinally extending laterally spaced strips.

11. Apparatus according to claim 9 wherein said lifting means comprises a bar of non-magnetic material having transverse sockets formed therein with both ends open, and strips of magnetic material secured to each edge of said bar over the ends of said openings for retaining said magnets in position.

HARRY E. STOVER.
